CLAIM

The ornamental design for the speaker, as shown, or as shown and described.

DESCRIPTION

FIG. 1 is a left front side perspective view of a speaker, embodying my design;

FIG. 2 is a right front perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is a reference view thereof, showing several individual units of the speaker in a stacked configuration.

The broken line portions of FIG. 9 are included to show unclaimed subject matter only and form no part of the claimed design.
